C. S. RYERSON:
CARBURETER.
APPLICATION FILED MAY 7, 1917.

Patented Aug. 26, 1919.

INVENTOR:
CHARLES S. RYERSON,
BY *Le Roy D. Dier*,
ATTORNEY.

UNITED STATES PATENT OFFICE.

CHARLES S. RYERSON, OF DETROIT, MICHIGAN, ASSIGNOR TO CADILLAC MOTOR CAR COMPANY, OF DETROIT, MICHIGAN, A CORPORATION OF MICHIGAN.

CARBURETER.

1,314,020.

Specification of Letters Patent. Patented Aug. 26, 1919.

Application filed May 7, 1917. Serial No. 166,899.

To all whom it may concern:

Be it known that I, CHARLES S. RYERSON, a citizen of the United States, and resident of Detroit, Wayne county, State of Michigan, have invented certain new and useful improvements in Carbureters, of which the following is a specification.

This invention relates to improvements in carbureters.

10 One of the objects of this invention is to provide improved automatic means for thinning out and breaking up into extremely fine particles, the hydrocarbon fuel before mixing it with air for forming an explosive mixture.

15 Another object of this invention is to vaporize a hydrocarbon fuel by discharging it against a rotatable flared tube, whereby the liquid is thinned out while at the same time being carried upwardly and outwardly, and providing means for subsequently mixing the highly attenuated fuel with air for forming a more stable and efficiently vaporized combustible mixture.

20 25 Another object is to greatly improve the vaporization and carburetion of a hydrocarbon fuel explosive, especially adapted for use in an internal combustion engine.

These, and various other objects, will more 30 clearly appear from the following description, taken in connection with the drawings which form a part of this specification and in which:

35 Figure 1 is a longitudinal vertical section of a carbureter, embodying a preferred form of my invention; and

Fig. 2 is a side elevation taken substantially at right angles to Fig. 1, showing portions broken away.

40 Referring to the drawings, 10 illustrates a float chamber comprising a shell, having concentrically arranged outer and inner walls 11 and 12 respectively. The upper end of the tapered tubular inner wall 12 is 45 formed interiorly thereof with threads 13 to which is connected an exteriorly threaded lower end of a tapered tubular portion 14 of a float chamber cover member 15. It is to be noted that the flexible gaskets 16 and 50 17 are arranged between the meeting surfaces of the cover member 15 and the inner and outer walls 11 and 12 of the float chamber.

55 A conduit 18 is formed in the lower part of the float chamber with an intake port 19 communicating with its interior, adjacent

the lower end thereof. The conduit is also provided with a boss 20, arranged in the center of the tubular wall 12. A nozzle 21 is adapted to be mounted in the boss 20 60 and to be secured therein as by a plug 22. It is to be noted that the nozzle inlet port 23 is in communication with the conduit inlet port 19 through the fuel passage 18. The tubular wall 12 is formed with a bell shaped 65 mouth 24, provided with a primary air intake port 25, which is adapted to be regulated by means of a valve 26 threaded as at 27 on a collar 28, which is secured as by a retaining member 29 to a stud 30, preferably 70 formed integral with the lower end of the fuel nozzle plug 22. A spring 31, and the force of gravity tend to return the valve member 26 to its closed position.

75 It will be noted that the tubular portions 12 and 14 of the float chamber and its cover member form a venturi shaped primary air intake passage 32. The usual float 33 is arranged within the chamber 10 pivotally connected as at 34 to an integral lug 35 in 80 the cover member, and adapted to operate a needle valve 36 for controlling the flow of fuel to the chamber from the supply passage 37.

85 The mixing chamber 38 is shown as an upwardly extending tubular portion formed integral with the cover member 15, and provided with a plurality of circumferentially arranged secondary air ports 39. A sleeve valve 40 is adapted to be slidably arranged in the interior of the mixing chamber with its lower end 41 normally resting against an interiorly formed shoulder 42 on the cover member. It is to be noted that a pair of pins 43 are adapted to be inserted 90 through axially extending slots 44, which are formed in the mixing chamber and suitably secured as by pressed fit or threading them to the sleeve valve 40 for preventing rotation of the sleeve while permitting a 100 reciprocating movement.

105 Formed adjacent the lower end of the sleeve is an inwardly extending spider 45, provided with a boss 46, in which may be suitably secured as by brazing, a downwardly extending bearing tube 47. A shaft 48 is adapted to have a radial bearing in the inturned portion 49 of the tube 47. A collar 50 may be secured as by a pin 51 to the shaft above the cage 45 for taking the 110 downward thrust between the shaft and cage.

An upwardly flared frusto conical tube 52

is normally arranged with its lower end 53 adjacent to the outlet 54 of the fuel nozzle and is provided adjacent its lower end with a spider 55, having a cone shaped member 56 secured to the lower end of the rotatable shaft 48.

It is to be noted that the interior of the lower end of the flared tube 52 is of slightly larger diameter than the adjacent portion of the fuel nozzle and surrounds the same in spaced relation, so that a small quantity of air may flow therebetween for lifting the fuel from the nozzle, and that means in the form of spiral vanes 57 may be suitably arranged on the exterior of the tube for rotating it as air is drawn through the primary air passage.

It will be observed that as the fuel is drawn from the nozzle, it will be deflected 20 to the interior surface of the rapidly rotating tube 52 by the cone shaped deflector 56 with the result that the fuel will be spread out over its surface and at the same time carried upwardly and outwardly over the flared 25 walls and finally discharged from the upper lip 58 where it will meet with the incoming primary air, and also with the auxiliary air after the ports 39 have been uncovered by the reciprocable sleeve 40.

30 It will be understood that as the velocity of the air passing through the primary air passage increases, it will exert a lifting action on the tube 52, in addition to spinning it, with the result that the upper end of the cone shaped deflector 56 will be carried against the bearing 49, and then lift the bearing tube 47 with the sleeve 40, gradually uncovering the auxiliary air ports 39.

The velocity of the rotating tube 52 for a 40 predetermined flow of mixture through the carbureter may be increased by the provision of another vane or spinner 59 shown as secured to the upper end of the shaft 48.

The auxiliary air ports 39 may if desired, 45 be regulated independently of the sleeve valve 40, by means of manually controlled slideable shutters 60, of any well known form.

The upper end of the shaft 48 may be rotatably mounted in a boss 61 which is centrally arranged in a cage 62 of a sleeve 63 which is provided with a pair of threaded trunnions 64, extending through oppositely disposed cam slots 65, formed adjacent the upper end of the mixing chamber 38. A 55 collar 66 may be secured as by a pin 67 to the upper end of the shaft 48 above the boss 61 and a spring 68 may be arranged on the shaft 48 between the lower end of the boss 61 and the shoulder 69 formed at the upper 60 end of the vane 59.

If it is desired to adjust the position of the rotatable tube 52 for predetermined conditions, relative to the nozzle 21, or to adjust the initial position of the auxiliary air 65 valve 40, the thumb nut 70 may be un-

screwed and the sleeve 63 rotated a sufficient distance to cause the pins 64 to ride upwardly or downwardly in the cam slots 65, thus raising or lowering the shaft 48, sleeve 40 and the tube 52.

The spring 68 is provided to decrease the lifting movement of the sleeve valve and the rotatable tube, after these parts have been raised a predetermined distance. Of course, the weights of the parts which are lifted 75 may be calculated to give a satisfactory floating structure without the use of the spring referred to.

It will be understood that while I have arranged to have a small quantity of air 80 pass through the rotatable fuel vaporizing tube, it is not necessary that this be done. On the other hand, I prefer that the fuel be discharged onto this tube and thoroughly broken up by centrifugal action and subsequently mixing it with the incoming air, that is, thinning by centrifugal action, the hydrocarbon fuel to substantially a gaseous form before it is mixed with the incoming air to form a combustible mixture. This 90 prevents any undesirable precipitation of unvaporized liquid particles.

While I have described and will specifically claim what I deem to be preferred forms and methods of carrying out my invention, it will of course be obvious to those skilled in the art, that various other modifications and changes may be made without departing from the spirit and scope thereof.

Having thus described my invention, 100 what I claim and desire to secure by Letters Patent, is:

1. In a carbureter, the combination with a fuel nozzle, a rotatable upwardly flared tube, having its lower end arranged adjacent the outlet of said nozzle, said carbureter having a primary air intake leading to the lower end of said tube, said tube being provided with vanes, said carbureter having an auxiliary air port arranged adjacent the upper end of said tube, and automatic valve means for regulating said latter port.

2. In a carbureter, the combination with a fuel nozzle, a rotatable upwardly flared tube, having its lower end arranged adjacent the outlet of said nozzle, said carbureter having a primary air intake leading to the lower end of said tube, said tube being provided with vanes and said carbureter having an auxiliary air port arranged adjacent the upper end of said tube, automatic valve means for regulating said latter port and an inter-connection between said valve and the support for said tube, whereby the position of said valve and said tube respectively are changed simultaneously.

3. In a carbureter, the combination with a fuel nozzle, an upwardly flared rotatable tube arranged adjacent the outlet thereof,

and means for adjusting the relation of said tube to said nozzle.

4. In a carbureter, the combination with a fuel nozzle, an upwardly flared rotatable tube arranged adjacent the outlet thereof, and means for automatically adjusting the relation of said tube to said nozzle.

5. In a carbureter having an air passage, in combination with a fuel nozzle and a rotatable flared tube arranged in line in said 10 passage, and means for rotating said tube by the flow of air through said passage.

In testimony whereof I affix my signature.

CHARLES S. RYERSON.
